UNITED STATES PATENT OFFICE

2,120,592

CONTAINER

William F. Leonhart, St. Louis, Mo., assignor to
 Owens-Illinois Can Company, a corporation of
 Delaware

Application March 24, 1937, Serial No. 132,693

10 Claims.

(Cl. 221—27)

The present invention relates to improvements in metal containers for holding oil, paint and varnish, etc., and relates more particularly to an improved pouring spout which will prevent spillage as the fluid contents are removed from said containers.

An object of the invention is the provision of a retractable pouring spout for a metal container which is formed as a permanent part thereof.

Another object of the invention is the provision of novel sealing means for supporting the spout within the head of the container.

A further object of the invention is the provision of a perforable seal for protecting the pouring spout until the container reaches the ultimate consumer.

Other objects and advantages will be in part apparent and in part pointed out during the course of the following description.

20 In the drawing:

Fig. 1 is a plan view of a container top to which my invention is applied;

Fig. 2 is a plan view of the pouring neck with the dust cover removed;

25 Fig. 3 is a plan view of the pouring spout with the perforable seal removed;

Fig. 4 is a vertical sectional view of a portion of a container to which the spout is applied, taken on line 4—4 of Fig. 1;

30 Fig. 5 is a detail sectional view similar to Fig. 4; and

Fig. 6 is a vertical sectional view showing the spout in pouring position.

Referring to Figs. 1 and 4 of the drawing, my invention is shown applied to a metal head 10 or cover, which is adapted to be used in connection with fluid containers such as pails or cans used for the transportation and storage of paints, oil and other liquids. The head is provided with an annular rolled bead 11 for engaging the rim 12 of a container 13. A gasket 14 within the bead 11 provides a seal between the head and body of the container and is maintained in position thereon by lugs 15 formed on the head and turned under the rim 12.

35 A well 16 is provided near one edge of the head 10 and has an inwardly inclined wall 17 in which the spout member is placed. The wall 17 slopes in a manner to permit a retractable spout 18 to project downwardly when the container is held in pouring position as shown in Fig. 6. A cup-like projection 19 formed integrally with the wall 17 extends outwardly therefrom and provides a seat for a gasket 20 and retaining ring 21 which 40 provide a seal and bearing for the retractable

spout member 18. The outer surface 22 of the cup 19 is scored at 23 to form a removable seal 24 or slug which is removed by tearing off when the container is to be emptied. In emptying the container, a hole may be punched in the opposite side of the cover to provide a vent for the escape of air and thereby prevent gurgling. Removal of the seal is aided by a scored tab 25 which may be punched inwardly by means of a suitable tool, such as a screw driver. The same tool may again be used to pry off the remainder of the seal. A removable dust cap 26 or cover is adapted to enclose the cup 19 and prevent foreign matter from entering the container after the seal 24 has been removed.

45 The spout 18 is formed from a cylindrical sheet metal tube 27 and is provided at its outer end with a rolled bead 28 for strengthening the tube and holding it against removal inwardly from the cup 19. A bail wire 29 or handle is pivoted to the outer end of the tube where it is accessible for drawing the spout into pouring position. The inner end of the spout is flanged outwardly at 30 to engage the retaining ring 21 when the spout is in pouring position. In the position shown in Fig. 25 6, the flange 30 seats against the ring 21 and is in sealing engagement therewith. The gasket 20 rigidly supports the tube for pouring.

The outer end of the tube 27 is provided with a longitudinal groove 31 extending through the lip 30 thereof, which slightly reduces the diameter of the end to permit easier withdrawal of the spout. The groove may also act as a vent for the escape of air from the container into which the contents are being poured.

35 In assembling the spout with the cover, the gasket and ring are placed over the spout prior to inserting in the cup 19. Pressure is applied to the outer surface 22 of the cup to "neck in" the portion adjacent the wall 17 as at 32 whereby the 40 gasket and ring are permanently held against removal. The present construction provides a readily accessible pouring means, which is permanently attached to the container and may be placed in operating position with a minimum of 45 effort.

Various changes in the size, shape and arrangement of parts may be resorted to without departing from the spirit of the invention or the scope of the appended claims.

50 I claim:

1. In combination with a metallic container having a cover, an inverted cup-like projection formed on said cover, a removable seal formed in the outer wall of said projection and defined by 55

a weakened area, and a pouring spout mounted within the projection and adapted to be exposed upon removal of the seal.

5 2. In combination with a metallic container having a cover, an inverted cup-like projection formed on said cover, a removable seal formed in the outer wall of said projection and defined by a weakened area, a pouring spout mounted within the projection, a sealing gasket surrounding said spout, and a resealing cap enclosing the outer end of said projection.

10 3. In combination with a metallic receptacle having a cover provided with a well near one edge thereof, a cylindrical projection having a closed outer end formed integrally with said cover within the well, a removable seal formed within the outer end of said projection and defined by a weakened area, a resealing cap enclosing said seal, and a spout mounted within said projection and adapted to be exposed upon removal of the seal.

15 4. In combination with a metallic receptacle having a cover provided with a well near one edge thereof, the bottom wall of said well being inclined inwardly from said cover, spout supporting means formed integrally with said inclined wall and projecting outwardly therefrom, a removable seal formed in the outer face of said support and defined by a weakened area to facilitate removal thereof, a cap for enclosing the outer surface of said projection, and a retractable pouring spout mounted within said support.

20 5. In combination with a metallic receptacle having a cover provided with a well near one edge thereof, said well having an inclined bottom wall, spout supporting means formed integrally with the bottom wall and projecting into said well, a seal forming the outer surface of said support and defined by a weakened portion to facilitate removal thereof, a resealing closure enclosing said seal and support, a retractable pouring spout mounted within the support, and means for moving said spout into operating position.

25 45 6. In combination with a metallic container having a cover provided with a well near one edge thereof, spout supporting means formed within the well and projecting outwardly therefrom, a seal forming the outer surface of said support and defined by a weakened zone, a retractable pouring spout mounted within said support, said spout comprising a cylindrical tube and having a flange at either end thereof, means

for moving the spout into operating position, and a closure cap for enclosing said support after the removal of said seal.

5 7. In combination with a metal container having a cover provided with a well near one edge thereof, spout supporting means formed integrally with the bottom wall of said well, a removable seal forming the outer surface of the support and covering a pouring opening, said seal defined by a weakened zone, a retractable 10 pouring spout mounted within said support, said spout comprising a cylindrical tube having a flange at either end thereof for limiting axial movement of the tube, a gasket surrounding the tube within the support, a retaining ring for 15 holding the gasket in sealing engagement with the tube and support, means for aiding the withdrawal of said tube into operating position upon removal of the seal, and a cap for enclosing the pouring opening.

20 8. A sheet metal container provided with a cover having a well formed therein, a sleeve integrally formed with the bottom of said well, a pouring spout slidably mounted within said sleeve, sealing means disposed between said 25 spout and the sleeve, and a removable seal integrally formed with and closing one end of said sleeve and concealing said pouring spout.

9. In combination, a container including a cover portion having a normally closed discharging opening therein, a removable seal for said opening integrally formed with the cover portion and defined by a weakened area, a tube slidably mounted in said opening and normally disposed in its entirety within the container, and means 30 rendered accessible by removal of the seal whereby the tube may be projected outwardly from the container in position to function as a pouring spout.

35 40 10. In combination, a container including a cover portion having a normally closed discharging opening therein, a removable seal for said opening integrally formed with the cover portion and defined by a weakened area, a tube slidably mounted in said opening and normally disposed in its entirety within the container, means rendered accessible by removal of the seal whereby the tube may be projected outwardly from the container in position to function as a pouring spout, and a cover operable to close the 45 discharging opening upon retraction of the tube into the container.

WILLIAM F. LEONHART.
